C. SEYBOLD

PAPER CUTTING MACHINE

Filed May 17, 1923

INVENTOR.
Charles Seybold

BY *Allen & Allen*
ATTORNEYS.

UNITED STATES PATENT OFFICE.

CHARLES SEYBOLD, OF DAYTON, OHIO.

PAPER-CUTTING MACHINE.

Application filed May 17, 1923. Serial No. 639,686.

To all whom it may concern:

Be it known that I, CHARLES SEYBOLD, a citizen of the United States, residing at Dayton, in the county of Montgomery and State of Ohio, have invented certain new and useful Improvements in Paper-Cutting Machines, of which the following is a full, clear, and exact description, reference being had to the accompanying drawing, forming part of this specification.

My invention relates to improvements in paper cutting machines in which a reciprocating knife is held by a knife bar, having bearings at each end, which operate in certain bearings, provided on the frame of the machine, or on the clamp, which holds the paper in place while cutting.

It has been found in practice, that where a very long knife blade is used, the hardness and resistance of the material to be cut, causes the knife to spring at or near the center, thus producing either a concave or convex cut in the material as the tendency of that particular knife may be.

My object is provide an additional, adjustable bearing, preferably in the form of a wedge, suitably situated to counteract any tendency of the knife to spring or bend out of its proper alignment.

I attain these objects by the mechanism illustrated in the accompanying drawing, in which—

Figure 1 is a front elevation of the upper portion of a paper cutting machine, with a section of the knife and knife bar broken away, showing the adjustable bearing.

Figure 2 is a vertical section on the line 2—2 of Figure 1.

Figure 3 is a plan view of the adjustable bearing.

Figure 4 is a front elevation of the adjustable bearing.

The clamp 1, which is the means of holding the material during the process of cutting, is recessed at 2 to admit the wedge member of the bearing 3, said member being provided at its upper end 4, with a sleeve 5, having a hole 6 (not threaded) to admit a screw stud 7, said stud being threaded and inserted in a threaded hole 8, in clamp 1, and secured by a locknut 9. The sleeve 5 on the wedge member 3 is then passed over the stud 7 first having passed a locknut 10 over the stud, and is secured in place by the locknut 11. By means of the locknuts 10 and 11, the bearing may be adjusted up-

ward or downward and finally locked in place when the desired adjustment has been attained.

It will appear obvious that any lubricant employed between this bearing and the knife or knife bar, would soil the paper stock. I have therefore provided in the face 12, of the wedge member 3, a number of recesses 13, inserted in which are a number of fiber plates 14, fastened to the wedge member by screws 15, these plates to bear against the back of the knife 16, and knife bar 17 thus forming a bearing contact that requires no lubrication.

As will be seen from this description and the accompanying drawings, my device provides a bearing surface at B, in addition to those usually employed at A—A. Should an imperfect knife show a tendency to make a concave cut, the defect may be remedied by adjusting the bearing downward by means of the adjusting nuts 10 and 11, thus forcing the knife bar and knife forward at the center; or in the case of the opposite tendency to produce a convex cut, an upward adjustment of the bearing would permit the knife bar to spring or bear in the opposite direction, and bring the knife into true alignment.

I am well aware that it would be possible to attain this result with a blade having a number of screws for adjustment; but in this case the adjustments would need to be very accurate in order to bring about perfect alignment at the cutting edge. Also my object could be accomplished by means of an adjustable wedge imbedded in the knife bar between it and the knife, instead of in the clamp. In either case the construction of the clamp member must be very deep and heavy to prevent any springage therein.

For this reason, and because the parts affected can be placed so as to be more easily accessible, I have preferred to carry out the principle of my invention in the manner of construction set forth in the above description.

Having thus described my invention, what I claim as new and desire to secure by Letters Patent, is:—

1. In a paper cutting machine having a reciprocating knife bar and knife, and a clamp for holding the material while cutting, an adjustable bearing for the knife intermediate its ends to prevent said knife

and knife bar from springing or bending out of alignment. 20

2. In a paper cutting machine having a reciprocating knife bar and knife, with bearings therefor at each end, and a clamp for holding the material while cutting, an adjustable additional bearing intermediate the end bearings inserted between the clamp and knife bar, to prevent said knife and 10 knife bar from springing or bending out of alignment.

3. In combination with a paper cutting machine having a reciprocating knife bar and knife with a clamp for holding the material in place while cutting, said clamp having a recess therein and a wedge-shaped bearing adjustable in said recess, said bearing being to exert or relieve pressure 15 against the knife blade and knife bar and

prevent them from springing or bending out of alignment. 20

4. In a paper cutting machine, having a reciprocating knife bar and knife with bearings therefor at each end and a clamp, an adjustable wedge-shaped bearing at or near the center between the bar and clamp and a screw stud for adjusting said bearing, said stud at one end being inserted into the clamp and suitable means for adjusting and holding the bearing in a definite position. 25

5. In a paper cutting machine, having a reciprocating knife bar and knife with bearings therefor at each end and a clamp, an intermediate bearing for the knife bar, said bearing being provided with bearing 30 surfaces comprising frictional material requiring no lubrication.

CHARLES SEYBOLD.
